UNITED STATES PATENT OFFICE.

GEORGE MCNEILL, OF DETROIT, MICHIGAN, ASSIGNOR TO MORGAN & WRIGHT, A CORPORATION OF MICHIGAN.

BEAD-WRAPPING APPARATUS.

1,296,991.

Specification of Letters Patent. Patented Mar. 11, 1919.

Application filed August 10, 1916. Serial No. 114,152.

To all whom it may concern:

Be it known that I, GEORGE MCNEILL, a citizen of the United States, residing at Detroit, in the county of Wayne and State of Michigan, have invented certain new and useful Improvements in Bead-Wrapping Apparatus, of which the following is a full, clear, and exact description.

This invention relates to bead covering apparatus. In the manufacture of tires it is customary to employ beads which are formed of hard rubber and serve to stiffen the tires at the edges. Usually the bead is tubed in the form of a ribbon of triangular cross-section and is then cemented and covered with rubber treated fabric which serves to strengthen the union between the bead and the fabric layers at the edges of the tire. The fabric covering operation is usually performed by hand. The apparatus of the present invention is designed to cover the bead with fabric mechanically, and in a continuous operation.

The invention can be readily understood from the following description taken in connection with the accompanying drawings in which—

Fig. 1 is a plan view of the apparatus. Fig. 2 is a side elevation of the apparatus. Fig. 3 is an enlarged cross-sectional view on the line 3—3 Fig. 2.

Fig. 4 is an enlarged cross-sectional view on the line 4—4 Fig. 2.

Figs. 5 to 9 inclusive are fragmentary detail views showing successive stages of the wrapping operation and the final trimming operation.

Fig. 10 is a cross-sectional view on the line 10—10, Fig. 2.

Fig. 11 is a cross-sectional view on the line 11—11, Fig. 2.

Referring now to the drawings, in which like characters of reference designate similar parts, the invention is shown to comprise a table 10 to which is secured a bed plate 11 from which rises a casing 12. To one side of the casing are attached feeding rollers 13—14, four pairs of covering rollers 15—16, 17—18, 19—20, 21—22, and a rotary cutter and shear 23—24. The bead 25 passes in substantially a straight line through the various mechanisms in the order above named, and is met by the rubber treated fabric strip 26 at the primary covering rollers 15—16. Alternate pairs of covering rollers

have their axes disposed at right angles to each other, as shown in Figs. 5 to 8, so that the fabric will be bent in a new direction by each succeeding pair of rollers and thus is shaped successively to cover the three sides of the triangular bead, beginning at one edge and ending at the same edge. A curved plate 27 is positioned between the first and second sets of covering rollers and assists said second set of rollers in bending the fabric. The edges of the fabric strip, which meet and overlap, produce a selvage or surplus fabric which is trimmed off as the bead passes between the cutter and shear 23—24, so that a butt joint of the edges of the fabric is made.

Referring more specifically to the details, the lower feeding roller 14 is positively rotated from a main drive shaft 28 by meshing gears 29—30. The upper feeding roller 13 is pivoted on a shaft 31 and is pressed by a helical spring 32 toward the lower roller. The bead is thus pressed by the upper roller against the rotating lower roller and thereby fed progressively into the machine. A control lever 33 for stopping the machine is connected in any suitable manner to the source of power (not shown) and hooks into a notch in a pivoted lever 34. The latter is dislodged by an arm 35 on the pivot shaft 31 of the upper roller when the upper roller drops down on to the lower roller after the rear end of the bead passes through the rollers and releases the control lever which then shuts off the power. The feeding rollers are shaped to conform partially to the contour of the bead and thus easily receive and guide the bead accurately to the wrapping rollers.

The upper roller 15 of the first pair of wrapping rollers is positively rotated by a gear 36 which meshes with the driving gear 29 of the lower feeding roller. The lower roller 16 is hinged to the casing by a frame 37 which is normally held in operative position by interlocking spring pressed latches 38—39. When the latches are released the roller 16 may be rocked down to facilitate threading of the initial ends of the fabric strip and bead between the rollers. The function of these two rollers is to press the bottom face of the bead into snug engagement with the strip of fabric and thus cause adhesion of the fabric to this face of the bead. The lower roller is provided with a

flange 40 for guiding the strip during its passage between the rollers, and the upper roller is provided with a circumferential groove 41 which receives the convex side of the bead and so guides the bead relatively to the fabric that the outer edge of the bottom face of the bead is in coincidence with the outer edge of the strip of fabric, as shown in Fig. 5. As shown in Fig. 4, the strip of fabric is guided accurately on to the lower roller by guides 42-43 which engage the edges of the strip while it passes over a rod 44 of the frame 37 on the way to the rollers. The flange 43 is moved by an adjusting screw 45 toward and away from the flange 42 to receive various widths of the fabric.

Adjacent to the second set of covering rollers is the above mentioned arched plate 20 which engages the unused laterally projecting portion of the strip shown in Fig. 5 and bends the same upwardly. The function of the second set of covering rollers 17-18 is to press the convex face of the bead against this upwardly bent portion of the strip of fabric and thus cause adhesion of this portion of the strip to this face of the bead. For this purpose the inner roller 17 is formed with a circumferential groove 46 into which the up-turned portion of the strip and convex face of the bead are forced by the outer roller 18, which is shaped peripherally to engage the concave face of the bead. As the strip of fabric leaves the roller 17 the bead is adherent with its bottom face and its convex face thereto, and the unused portion of the strip projects outwardly beyond the bead as shown in Fig. 6. Both the inner roller and the outer roller are positively rotated in unison to effectively press the fabric into snug engagement with the bead, and for this purpose, as shown in Fig. 10, the shafts 47-48 of the rollers are connected by meshing gears 49-50. A drive shaft 51 journaled in the casing rotates the shaft of the inner roller 17 by meshing gears 52-53 and is itself rotated as shown in Figs. 1 and 2, by a chain drive 54 from the shaft of the upper roller of the first set of covering rollers. The outer roller 18 is hinged to the shaft housing 55 by a pivoted yoke 56 and is spring pressed toward the inner roller by a helical spring 57 to force the bead and strip into the groove of the inner roller as above explained.

The function of the third set of covering rollers 19-20 is to bend the strip downwardly over the concave face of the bead and press the upper rounded corner of the bead against this bent portion to cause adhesion of this portion of the strip to this corner of the bead. For this purpose the upper roller 19 is formed with a circumferential groove 58 which receives the unused portion of the strip shown in Fig. 6

and deflects the same downwardly. The bead with the fabric strip adherent to two of its faces is forced into said groove by the lower roller 20 and the upper rounded corner of the bead is thereby pressed against the downwardly bent part of the strip. As the strip leaves the roller 19 the bead is adherent thereto with its bottom face, convex face, and upper rounded corner, and the unused portion of the strip projects downwardly along and beyond the concave face of the bead, as best shown in Fig. 7. Both rollers are rotated in unison to effectively press the fabric into snug engagement with the bead, and for this purpose, as shown in Fig. 11, the shafts 59-60 of the rollers are geared together by meshing gears 61-62, and the shaft 59 of the upper roller is positively driven by a chain drive 63 from the shaft of the upper roller of the first set of covering rollers. The lower roller 20 is hinged to the casing by a pivoted yoke 64 and is spring pressed toward the upper roller by a helical spring 65 to force the bead and strip into the groove of the upper roller as above explained.

The function of the fourth set of covering rollers 21-22 is to press the downwardly bent unused portion of the strip shown in Fig. 7, into snug engagement with the concave face of the bead and thus cause adhesion of this portion of the strip to this face of the bead. For this purpose the roller 21 is formed with a circumferential groove 66 into which the bead with the strip adherent to two faces and one corner thereof is forced by the outer roller 22, which is shaped to conform to the curvature of the concave face of the bead and presses the strip against this face of the bead. As the strip emerges from between the rollers 21-22 the bead is adherent throughout to the strip, and the unused portion of the strip projects downwardly below the bead and overlaps the first applied edge of the strip at the lower outer edge of the bead. In this instance also, both the inner roller and the outer roller are positively rotated in unison to effectively press the fabric into snug engagement with the bead and as the gear mechanism, etc., is a duplicate of the mechanism described in connection with the second set of covering rollers 17-18, a description thereof will be dispensed with. These rollers are driven by a chain drive 67 from the drive shaft 51 of the second set of covering rollers.

The fabric covered bead passes from the final set of covering rollers to the rotary cutter 23 and shear 24 which are positioned to intercept the surplus unused fabric at the lower edge of the bead, and cut off the same so that a butt joint is produced at the meeting of the edges of the strip. During the cutting operation, the bead is supported opposite the cutter and shear by rollers 68 each

having a circumferential groove 69 to receive the bead as shown in Fig. 9. The cutter is rotated at a high rate of speed and for this purpose, as shown in Fig. 3, the cutter shaft 70 is driven by meshing gears 71—72 from a shaft 73 which is in turn driven by meshing gears 74—75 from a shaft 76 of one roller of a set of rollers about to be described. The shear is adjusted toward or 10 away from the knife by an adjusting screw 77 and is locked in adjusted positions by a set screw 78.

After the surplus fabric is trimmed off the covered bead, the latter passes between a set 15 of rollers 79—80 which are shaped to nearly surround the bead and serve to press the fabric throughout into intimate contact with the bead, and also coat with the final set of covering rollers 21—22 in progressively 20 advancing the bead past the cutter and shear. This final set of rollers is driven by gear mechanism which is a duplicate of the gear mechanism above described in connection with the third set of covering rollers 25 19—20 consequently further description is unnecessary. The rollers 79—80 are driven by a chain drive 81 from the drive shaft of the final set of covering rollers as shown in Fig. 2.

It is thought that from the above description the operation of the machine will be clearly understood, and that further detail description of the operation will not here be necessary.

Having thus described my invention, what I claim as new and desire to protect by Letters Patent is:

1. Bead wrapping apparatus, comprising means for wrapping a strip of fabric about 40 a bead, means for cutting off surplus fabric at the meeting edges of said strip, and means for progressively moving the bead during the wrapping and cutting operations.

2. Bead wrapping apparatus, comprising 45 means for initially applying an edge portion of a strip of fabric to one face of a bead,

means for wrapping the strip about the bead to meet the first applied portion at one edge of the bead, and means for cutting off surplus fabric at the meeting edges of the strip. 50

3. Bead wrapping apparatus, comprising means for primarily applying a strip of fabric wider than the bead to one face of a bead, means for folding the projecting edge portion of the strip about the bead to overlap 55 the first applied portion at an edge of the bead, and means for cutting off the surplus fabric from the meeting edges of the strip.

4. Bead wrapping apparatus, comprising feeding means, means for wrapping a strip 60 of fabric about the bead, and means automatically operated by the bead to stop the feeding means and the wrapping means when the end of the bead passes through the feeding means. 65

5. Bead wrapping apparatus, comprising power driven rollers adapted to successively bend over and wrap a strip of fabric about a bead beginning at one edge and ending at the same edge, and a power driven knife positioned to intercept and cut off surplus fabric at the meeting edges of the strip. 70

6. Bead wrapping apparatus, comprising feeding means, means for wrapping a strip 75 of fabric about the bead, means for cutting off surplus fabric at the meeting edges of the strip, and means automatically operated by the bead to stop the feeding means and the wrapping means when the end of the bead passes through the feed means. 80

7. Bead wrapping apparatus, comprising means for wrapping a strip of fabric about a bead, cutting-means arranged in a plane not passing through the bead for shearing off surplus fabric at the meeting-edge of said strip, and means for progressively moving the bead during the wrapping and cutting operations. 85

Signed at Detroit, Mich., this 28th day of July 1916.

GEORGE McNEILL.
